MOP HAVING TRIANGULAR COMPRESSIBLE
CLEANING ELEMENT

Harry B. Toombs, New York, N. Y.

Application December 20, 1949, Serial No. 133,980

1 Claim. (Cl. 15—119)

1

This invention relates to a structurally and functionally improved mop and especially a floor mop.

It is an object of the invention to furnish a device of this type which will incorporate an improved wringer structure such that water collected by the head of the mop may be readily expelled so that the device will be ready for re-use.

A further object is that of providing a head structure for a mop and which structure will embody a novel and improved arrangement of parts.

An additional object is that of furnishing an apparatus embodying relatively few parts each 15 individually simple and rugged in construction which parts may be manufactured by quantity production methods and assembled to furnish a rugged unit capable of being used for long periods of time with freedom from all difficulties, and in which, moreover, renewal of the parts may be achieved with minimum efforts.

With these and other objects in mind reference is had to the attached sheet of drawings illustrating one practical embodiment of the invention and in which:

Fig. 1 is a side view of the mop assembly;

Fig. 2 is a face view thereof;

Fig. 3 is a plan view of the mop carrying portion or head of the apparatus;

Fig. 4 is a view similar to Fig. 3, but showing the parts in a different position;

Fig. 5 is a sectional view of the outer portion of the apparatus including the mop taken along the lines 5—5 and in the direction of the arrows as indicated in Fig. 4; and

Fig. 6 is a fragmentary view of the outer or head portion of the apparatus and showing the parts of the same in the position illustrated in Fig. 4.

Referring primarily to Figs. 1 and 2, the 40 numeral 10 indicates a handle or actuating rod of any desired type and material. The numeral 11 generally designates the head of the mop which will be hereinafter described in detail. Slidably mounted upon the handle 10 is an actuating collar 12, to which the outer ends of links 13 are pivotally secured. Beyond these links further links 14 in the form of bars or struts are disposed. The ends of links 14 are pivotally secured as at 15 to the mop head. Intermediate 45 their ends these links are pivotally supported by a collar 16 or other part slidably mounted upon handles 10. The inner ends of links 14 are pivotally connected as at 17 to the adjacent ends 50 of links 13.

2

The head portion 11 of the mop comprises a holder and an assembly to move in contact over a surface to be cleaned. The assembly, according to the present invention, includes a stack of 5 layers 18 preferably of sponge rubber and generally of semi-circular configuration. These are disposed with their convex or curved edges extending in an outward direction. They are mounted free from compressive action upon a rod 19 which may have headed outer portions 20. As illustrated, these headed portions may be in the form of bumpers so as to prevent or minimize marring of furniture and other surfaces which they might contact.

The mounting portion of the head includes two pairs of links 21 and 22. The individual links of each pair may comprise wedge-shaped bodies. The reduced end portions of the links providing the pair 21 are overlapped and pivotally connected 20 as at 23. The outer ends of these links or plates present a dimension of maximum width and the links of different pairs are overlapped and connected as indicated at 24. Straps 25 may be movably carried by the pivots 23 and furnish a point 25 of pivotal connection for the links 14. Likewise the pivots 24 preferably mount supporting plates in the form of base portion 26 from which walls 27 extend upwardly. The latter are formed with inwardly and upwardly extending slots 28.

The dimensions of slots 28 should be such that 30 they will accommodate the rod 19, but will not permit of the passage of the headed portions 20 thereof. A further link or bar 29 is mounted at a point centrally of its length as indicated at 30 by handle 10. Its opposite ends are pivotally connected as at 31 to one each of the individual links or plates providing pairs 21 and 22.

Due to the resiliency of the layers 18 the parts will normally assume the positions shown in Figs. 1, 2 and 3. The action of gravity will assist in such positioning if the mop is stored in a position at which its head extends upwardly; the weight of the actuator and connected links assuring this result. As will be apparent in normal use the mop may be disposed to have its head extended downwardly and may traverse a surface to be cleaned in the usual manner. Such cleaning will be especially effective in view of the configuration of surface-contacting elements.

When a renewal of the mop head or elements is 50 desirable, then this may readily be achieved by simply depressing rod 19 downwardly within the vertical portions of slots 28 and until the latter may ride upwardly within the inclined portions 55 of these slots. A reversal of this procedure will

enable a new head part to be disposed in mounted position.

When it is desired to wring the mop or, in other words, expel the moisture contained within the elements 18 of the head portion thereof, all that is necessary is for an operator to project the actuator 12 along the handle 10 and in the direction of the head. With such projection the adjacent ends of links 13 and 14 will be swung outwardly. This will result in the ends of links or straps 25 mounting the pivots 15 also being swung outwardly. Accordingly, the parallel links movement embracing the links or plates 21 and 22 will be moved from the position shown in Fig. 3 to that shown in Fig. 4. Under these circumstances, plates 27 will be shifted towards each other or in the direction of the pivot 30. Consequently elements 18 will be compressed along rod 19 between these plates and the excess liquid will be squeezed therefrom. As the actuator is retracted, the parts will reassume the position shown in the first three figures. Accordingly, an efficient wringing of the mop assembly is achieved.

As will be noted, due to the width and curved edge configuration of the elements 18 providing the mop head, the latter may be moved in cleaning contact with the floor surface and even under articles of furniture closely above that surface. To this end, the handle may be shifted to assume a substantially horizontal position. Individual elements 18 may be removed from rod 19 for the purpose of renewal or cleaning. Such elements may be economically provided from scrap or otherwise.

Thus, among others, the several objects of the invention as specifically aforesaid are accomplished. Obviously numerous changes in con-

5

struction and rearrangement of the parts might be resorted to without departing from the spirit of the invention as defined by the claim.

I claim:

In a mop having a handle and a head on said handle the combination of two opposed pairs of plates oppositely positioned with respect to said handle and coupled to provide a parallel link motion, end walls pivotally supported on two of said plates in line with their point of pivotal connection, a compressible cleaning element mountable adjacent to said plates, a rod insertable through said element and mounted in said end walls receiving said rod, actuating portions secured in line with the other pivots of said plates, said actuating portions being movably mounted on said handle to shift said plates and cause said end walls to move inwardly towards each other whereby said compressible element may be compressed equally from both ends with said handle in a vertical position.

HARRY B. TOOMBS.
